No. 742,697.

UNITED STATES PATENT OFFICE.

SIDNEY B. MARTIN, OF MCKEE, KENTUCKY; KENNADA MORRIS, ADMINISTRATOR OF SAID MARTIN, DECEASED, ASSIGNOR TO AD W. CREEKMORE AND HORATIO G. CREEKMORE, OF LEXINGTON, KENTUCKY.

STILL.

SPECIFICATION forming part of Letters Patent No. 742,697, dated October 27, 1903.

Application filed May 4, 1903. Serial No. 155,587. (No model.)

To all whom it may concern:

Be it known that I, SIDNEY B. MARTIN, a citizen of the United States, residing at McKee, in the county of Jackson and State of Kentucky, have invented certain new and useful Improvements in Stills, of which the following is a specification.

My invention relates to improvements in stills, and one object of my invention is to provide a still which will be continuous and easy of operation.

Another object of my invention is the provision of an article of this character which will be very simple of construction and inexpensive of production.

Figure 1 is a side elevation of my complete apparatus. Fig. 2 is a vertical central sectional view thereof.

The invention consists of the combination and arrangement of parts substantially as shown in the drawings, in which—

The letter A designates the boiling-tank, B the heating-tank, C the pipe leading from said boiling-tank to the doubler and low-wine receptacle D, from which receptacle leads the pipe E, which passes to and forms a worm in the heating-chamber B and then passes to the cooler F. The boiler A is provided with the openings a and b, the former to admit air and the latter to let out the slop. The doubler D is also provided with a waste-outlet c and an opening d in its top, through which the low-wine is poured into the doubler. The boiler A and heater B are separated by a suitable partition e, in which an opening is provided, and a cork f for said opening, through which the beer passes from heater to boiler.

The operation of distillation is as follows: The cork for the opening in the partition separating A and B is removed to let the beer into the boiler, after which it is replaced and the upper chamber or heater is filled with beer. The vapor arising from the boiling-chamber

passes through pipe C into the low-wine tank 45 D, into which has been poured through opening d enough low-wine to cover the end of pipe C. The vapor then passes through pipe E, heating in its passage the beer in heater B, and thence through a continuation of the same 50 pipe, connecting heater and cooler through the worm in the cooler, whence the resultant whisky is drawn off. When the beer in the boiler has boiled off, the beer in the heater warmed by pipe E is let through the opening 55 in the partition, after which the heater is again filled to be ready when the beer in the boiler has again boiled off.

It will thus be seen that I provide a still which is almost continuous in operation. 60

When necessary, the slop from boiler may be drawn off through the opening a, and for the purpose of drawing off the waste from the doubler I provide the opening c.

Having thus described my invention, what 65 I claim as new, and desire to secure by Letters Patent, is—

The still herein shown and described, consisting of the tank divided by a partition to form a boiling and heating chamber, the boiling-chamber having an air-inlet and a discharge-opening, and the partition having an opening, a plug for controlling said opening, a doubler and a cooler, the doubler having a filling and discharge opening, the pipe 70 leading from the doubler and formed with a worm arranged in the heating-chamber and passing from the heating-chamber and formed with a coil in the cooling-chamber and the pipe leading from the partition in the tank to 75 the lower portion of the doubler.

In testimony whereof I affix my signature in presence of two witnesses.

SIDNEY B. MARTIN.
